UNITED STATES PATENT OFFICE.

CHARLES A. MILLER, OF STAMFORD, CONNECTICUT, ASSIGNEE TO THE YALE & TOWNE MANUFACTURING COMPANY, OF STAMFORD, CONNECTICUT.

TIME-LOCK FOR SAFES AND VAULTS.

991,629.

Specification of Letters Patent.

Patented May 9, 1911.

Application filed October 21, 1909. Serial No. 523,896.

To all whom it may concern:

Be it known that I, CHARLES A. MILLER, of Stamford, in the county of Fairfield and State of Connecticut, have invented certain new and useful Improvements in Time-Locks for Safes and Vaults; and I do hereby declare the following to be a full, clear, and exact description of the invention, such as will enable others skilled in the art 10 to which it appertains to make and use the same.

My invention relates to an improvement in time locks for safes and vaults.

In certain sections of the country where 15 hold-ups or robberies are liable to occur during the day time, it is desirable to safeguard the regular time mechanism of the lock, by means that will actuate the time lock unlocking lever at regular intervals, say once 20 each hour, retain the said lever in unlocked position for a stated number of minutes and then lock up again. It is evident that in robberies of this character, quickness is necessary, and with the safe door guarded and 25 locked, say eleven-twelfths of the time during the day, the chances would be largely in favor of the attempt being made at a time when the door was locked.

The object of this invention is to provide, 30 in addition to the customary timelocks which guard a safe door ordinarily from the close of one banking day to the opening of the following banking day, an improved device whereby when desired the safe may be 35 kept locked all the time except at certain desired short intervals. The customary timelock taking care of the locking at night the improved supplementary device may then go into operation so that the safe or vault 40 may be locked during the larger portion of the day; *i. e.* for instance, for the whole or every hour during the day except that there may be one, two, or more minutes out of each hour when the safe can be opened, but 45 if the safe should not be opened during that predetermined period then the timelock would automatically lock up again. This special supplementary device may be used either in connection with the customary 50 timelock, and arranged to operate on the locking lever of said timelock, or it may be employed in connection with said ordinary timelock but have an independent locking mechanism of its own; or, it may be em-

ployed by itself separately on a door. In 55 the device illustrated, both time mechanism actuate the same bolt unlocking lever which releases or sets free the bolt mechanism of the safe or vault, hence with this particular construction the main time mechanism is in 60 operation during the period the supplemental time mechanism is set for operation, as well as during the period when the supplemental time mechanism is not in operation.

In the accompanying drawings, Figure 1 65 is a view in plan of my improved lock. Fig. 2 is a view in plan parts being removed and showing particularly the motors and mechanism for tripping the latter. Fig. 3 is a view in plan of the supplemental time mechanism. Fig. 4 is a view in transverse vertical section of Fig. 1 and Fig. 5 is a bottom plan view, the bottom or base plate being removed.

1 represents one of the ordinary triple 75 movement time locks, and 2 the unlocking lever, the latter being designed for connection with the bolt mechanism of the safe or vault door, and actuated by the time mechanism 1 for releasing the bolt mechanism at a 80 predetermined time in the usual and well known manner.

3 represents the supplementary mechanism, which embodies the features of my invention. This mechanism comprises a time 85 mechanism consisting of two separate main springs inclosed in the casings 4 operating upon a spindle 5 carrying the dial 6, and two motors 7 which operate to actuate the unlocking lever 2, when tripped or released 90 by the supplementary or day time mechanism. The employment of two mainsprings in the time mechanism, and the same number in the motor is not essential, a plurality being employed simply as a precautionary 95 measure or safeguard, so that if one should fail the other or others would operate to release the bolt work mechanism at the proper time. The dial 6 makes one complete revolution in sixty minutes, and is marked off 100 into sections, each section representing one minute and is also provided with threaded holes 6^a located at five minute intervals.

8 are pins adapted to be screwed into the holes 6^a in the dial and project below same, each pin being provided with an enlarged head by which it may be grasped and manipulated. For the purposes of illustration

I have shown the pins 8 located in two adjacent holes, thus representing an interval of five minutes that elapses in the travel of the pins past a given point.

5 Pivotedly secured to the rear face of the outer plate 8^a of the supplementary mechanism 3, is the lever 9 the lower end of which is bent upwardly, passes through an opening in the plate 8^a and is normally held 10 in the path of the pins 8, by the spring 10. The opposite end of lever 9 is bent rearwardly toward the intermediate plate 11 of the supplementary mechanism 3, and is provided with an enlarged end 12 having a 15 cam slot 13 therein, in which rests the pin 14 carried by releasing lever 15. This lever 15 is pivoted to the rear face of the intermediate plate 11, and the pin 14 carried thereby at one end, passes through a 20 hole in the intermediate plate and rests within the cam slot in the lever 9. The opposite end of the releasing lever 15, rests in contact with the pin 16 secured to the pawl 17, the latter being carried by a post 25 18 mounted at its outer end in the intermediate plate 11, and at its rear end in the rear plate 19. The pawl is provided with a tooth 20 which moves in contact with a circular flange 21 carried by a toothed wheel 30 21^a driven by the two spring motors 7, and is normally held in contact with said flange by the spring 23.

Each motor 7 is provided with a key spindle 23^a which passes through the intermediate plate 11 so as to be accessible from the front.

The flange 21, is provided with diametrically located slots 24, into which the tooth 20 of the pawl 17 drops. When the tooth of 40 the pawl is in either slot 24, the wheel carrying the flange is held at rest. When however the pawl is pushed out of the slot by the releasing lever 15, the spring motors 7 are free to rotate the wheel 21^a and its 45 shaft 21^b. Secured to the latter in rear of the inner plate of the supplementary mechanism, is the disk 25 carrying a rearwardly projecting pin 26 which latter engages one end of the lever 27 pivoted to the lock case, 50 the opposite end of said lever resting in front of a lug 28 on the unlocking lever 2. This unlocking lever is normally held in its locking position by a spring; hence when lever 27 is actuated as hereinafter described, 55 it retracts lever 2 and holds it retracted for a stated interval of time (five minutes in the construction as illustrated) and then releases it, thus permitting it to move to its projected position.

60 As shown in the drawings, the pins 8 in the dial are located in two adjacent holes, representing an interval of five minutes. As this dial is revolved by the supplementary or day time mechanism 3, the first pin 8 65 strikes the upturned end of lever 9 and

turns same slightly. This movement of the lever 9 causes its cam slot 13 to move the pin 14 carried by releasing lever 15 thus forcing the latter against the pin 16 on pawl 17, and moving the tooth 20 of the pawl 17 70 out of the slot 24 in flange 21. This disengagement of the pawl and flange, releases the motors 7 and permits the latter to actuate the shaft 21^b which as before explained carries the slotted flange 21. As the first 75 pin on dial 6 leaves the end of lever 9, the parts being spring actuated assume their normal positions, thus releasing pawl and permitting its tooth to ride on the outer surface of flange 21, hence when the next slot 80 24 in latter reaches the tooth of the pawl, the latter drops into said slot and stops the motors. As there are two slots 24 located diametrically opposite each other it will be seen that the shaft 21^b makes but half a 85 revolution at each release of the motors, and in the first half revolution, the pin 26 on disk 25 carried on the lower end of said shaft, shifts lever 27 in a direction to retract the unlocking lever and holds same in its 90 retracted position for the period of time represented by the distance between the pins 8, in the present instance, five minutes. At the expiration of the five minutes, the second pin 6 coming in contact with lever 9, shifts 95 the parts as above explained and again withdraws the tooth 20 of pawl 17 from the slot 24 in flange 21, thus permitting shaft 21^b to make another half revolution, thus restoring lever 27 to its original position and 100 permitting the unlocking lever 2 to move back to its normal projected or locking position. This release of the bolt mechanism will occur once each hour, and for a period of five minutes at each release. The lever 105 9 is also engaged by the pin 29 on lever 30 pivoted to the outer face of the outer plate 8^a of the supplementary mechanism 3. This lever 30 is also spring actuated, but is designed to be moved by hand against the action of its spring so as to move lever 9 out of the path of the pins 8, a spring catch 31 being provided for holding lever 30 depressed, thus disconnecting the supplementary mechanism from the regular time lock 110 1. This condition of course is the one that will obtain at night, when it is not desired to have any periods when the safe can or will be unlocked. When the supplementary mechanism is disconnected as above described, 115 the motor will be braked and restrained from acting, by the locking pin 32 carried by the spring arm 33, the latter being actuated by the lever 30, engaging lug 34 carried by said spring arm 33. This lug is 120 located in the path of the lever 30 when the latter is moved to a position to carry lever 9 out of the path of the pins 8, and when engaged by said lever, will be depressed thereby and thus move the locking pin 32 130

into the path of a moving part of the motor and thus lock the latter against movement. By means of this lever 30, the attendant, can by slightly moving same test his supplementary mechanism before putting it into use for the day, which should of course be done to see that everything is working properly, and by moving it back until it engages the spring catch, he disconnects the 5 motors, thus leaving the bolt mechanism solely under the control of the main time lock, which is the condition the lock should be in after close of business for the day.

The main time lock mechanism may be 15 set to unlock the lock at any predetermined time, and the supplemental time movement unlocks it and locks it at shorter fixed intervals during the time it is set to be released by the main time movement, hence 20 when the time arrives for the bolt mechanism to be unlocked by the main mechanism, the latter retracts the unlocking lever in the usual manner and holds it retracted until the movements are again wound up and set 25 for another period.

It is evident that many slight changes might be resorted to in the relative arrangement of part shown and described without departing from the spirit and scope 30 of the invention hence I would have it understood that I do not confine myself to the exact construction and arrangement of parts shown and described, but,

Having fully described my invention what 35 I claim as new and desire to secure by Letters-Patent, is:—

1. The combination with a main time lock movement, and its bolt unlocking lever, of a motor also connected with said 40 locking lever, a supplemental time movement, and means actuated at regular intervals by the supplemental time movement, for releasing the motor whereby the latter operates to retract the unlocking lever, hold it retracted for a fixed interval, and then release it at the end of each interval.

2. The combination with a main time lock 45 for bolt mechanism and its unlocking lever, of a motor connected with said unlocking lever for actuating same, a supplemental time movement having a rotating dial, and means actuated by projections on the dial for starting and stopping the motor at fixed 55 intervals whereby the unlocking lever will be actuated to release the bolt mechanism at fixed intervals during the day.

3. The combination with a main time lock 60 for bolt mechanism, and its unlocking lever, of a motor connected with said unlocking lever for actuating same, a supplemental time movement having a rotating dial, pins adjustably secured in said dial, and means actuated by said pins for starting and stop- 65 ping the motor at fixed intervals whereby

the said unlocking lever will be actuated to release the bolt mechanism at fixed intervals during the day.

4. The combination with a main time lock 70 for unlocking or releasing the bolt mechanism of a safe door once for each winding of the said mechanism, of a supplemental time movement, a rotating dial actuated by the latter, and means actuated and controlled by said rotating dial for unlocking 75 or releasing said bolt mechanism, at certain fixed intervals prior to the time the main time mechanism is set to operate said means operating to relock said bolt mechanism at the end of each interval.

5. The combination with a main time 80 mechanism and a bolt unlocking lever actuated thereby, of a motor also connected to said bolt unlocking lever for actuating same, a supplemental time mechanism, a dial rotated by said time mechanism, two pins adjustably secured to said dial, means for holding the motor against movement, and means actuated by the pins carried by the dial for first releasing the motor from 85 said holding means whereby the bolt unlocking lever will be actuated to release the bolt, said lever being held in its unlocking position for the period of time represented by the distance between the pins on the dial, 90 whereupon the motor will be released to restore the bolt unlocking lever to its locking position, said operation occurring once at each revolution of the dial.

6. The combination with a main time 100 mechanism and a bolt unlocking lever actuated thereby, of a motor also connected to said bolt unlocking lever for actuating same, a supplemental time mechanism, a dial connected to said supplemental time mechanism 105 and adapted to make a complete rotation once each hour, pins detachably secured to said dial, means for holding the motor against movement and means actuated by the pins on the dial for actuating the motor 110 holding means, whereby the motor will be released twice during each revolution of the dial.

7. The combination with a main time 115 movement and a bolt unlocking lever actuated thereby, of a motor also connected to said lever for moving same to its unlocking position, a supplemental time movement for starting and stopping the motor at regular intervals, and means for disconnecting the supplemental time movement from its motor, and for locking the motor, thus leaving the unlocking lever under the sole control of the main time movement.

8. The combination with a main time 125 movement for releasing the safe bolt work once at each winding of said movement, of a supplemental time movement, a motor connected with the bolt work releasing means and means actuated by the supplemental 130

- time movement for starting and stopping the motor at regular intervals, whereby the bolt work will be released and relocked at regular intervals prior to the time the main time mechanism may be set to unlock the bolts.
9. The combination with a main time lock and a bolt unlocking lever actuated thereby, of a motor connected with said bolt 10 unlocking lever for actuating same, a supplemental time movement, a graduated dial rotated by said latter time movement and having a series of holes therein located at regular intervals apart, pins removably secured in said holes, and means actuated by the pins in the dial for starting and stopping the motor at regular and fixed intervals.
10. The combination with a main time 20 movement for releasing the safe bolt at a predetermined time, and a bolt unlocking lever actuated by said main time movement, of a motor also connected with said unlocking lever, a supplemental time movement, 25 means connecting the motor and supplemental time movement whereby the motor will be started and stopped to release and relock the bolts at regular intervals, and means for disconnecting the supplementary 30 mechanism from the bolt unlocking lever, thus leaving the latter solely under the control of the main time movement.
11. The combination with a main time lock having a bolt unlocking lever, of a supplemental time movement coacting with the 35 unlocking lever of the main time lock for unlocking the bolts at certain fixed intervals and for automatically relocking said bolts at the expiration of each interval, substantially as described.
12. The combination with a main time lock and bolt unlocking mechanism actuated thereby, of a supplemental time movement, means controlled thereby and engaging the 45 unlocking mechanism for retracting and holding it retracted for certain fixed periods during the day.
13. The combination with a main time mechanism for releasing the bolt mechanism 50 of a safe door, once at each winding, of a supplemental mechanism coupled up to the bolt mechanism releasing means of the main time lock, and adapted to move same to unlocking position at certain fixed intervals 55 prior to the time for which the main time lock is set, and to permit it to return to its locking position after the expiration of each interval.
14. The combination with a main time 60 lock mechanism for unlocking or releasing the bolt mechanism of a safe door for each winding of the said mechanism, of a supplemental time movement coöperating with the bolt unlocking lever of the main time movement, for unlocking or releasing said bolt

mechanism, holding it in its unlocking position and then releasing same at certain fixed intervals prior to the time the main time mechanism is set to operate.

15. The combination with a bolt releasing 70 means, a time movement having a rotating dial, and a motor operatively connected with said bolt releasing means for actuating same, of means actuated by projections on the dial for starting and stopping the motor at 75 fixed intervals whereby the bolt releasing means will be actuated to release the bolt at fixed intervals during the day.

16. The combination with a bolt releasing 80 means, a time movement having a rotating dial, pins removably mounted in said dial and projecting therefrom, and a motor operatively connected with said bolt releasing means for actuating same, of means actuated by the pins projecting from the dial for 85 starting and stopping the motor at fixed and determinable intervals whereby the bolt releasing means will be actuated to release the bolt at intervals during the day.

17. The combination with a bolt releasing 90 means, a motor operatively connected thereto, a time mechanism, a dial rotated by said time mechanism and two pins movably mounted in said dial and projecting therefrom, of means actuated by the pins on the 95 dial for releasing the motor whereby the bolt releasing means will be actuated to release the bolt, said bolt releasing means being held in its releasing position for a period of time represented by the distance between the pins in the dial, whereupon the motor will be released to permit the bolt releasing means to assume its original position, said operation occurring once at each revolution of the dial.

18. In combination with releasing means 105 for the bolt work of a safe door, of time mechanism, a motor, means operatively connecting the motor and said bolt work releasing means, and a device actuated by the time mechanism and controlling the operation of the motor whereby said releasing means will be actuated at intervals to release the bolt work.

19. In combination with releasing means 115 for the bolt work of a safe or vault, of time mechanism including regulating devices, and a motor controlled by said regulating devices for actuating said releasing mechanism to release the bolt work for a short period and at the end of such period permitting said 120 releasing means to assume its locking position.

20. The combination with a bolt releasing 125 means, a time movement and, a motor, of means actuated at regular intervals by the time movement for releasing the motor whereby the latter operates to retract the bolt releasing means, hold it retracted for a fixed interval, and then release it at the end of each interval.

21. The combination with bolt releasing means, a time movement and a motor connected with said releasing means, of means actuated by the time movement for starting and stopping the motor at regular intervals whereby the releasing means will be actuated at regular intervals while the time movement is in operation.

In testimony whereof, I have signed this specification in the presence of two subscribing witnesses.

CHAS. A. MILLER.
